GAME BOARD

Reuben B. Klamer, Pacific Palisades, and Bill Markham,
Buena Park, Calif., assignors to Link Research Corporation

Filed July 26, 1960, Ser. No. 61,516

Term of patent 3½ years

(Cl. D34—5)

FIG. 1.

FIG. 2.

FIG. 1 is a top plan view of a game board showing our new design; and

FIG. 2 is a perspective view thereof in a partially opened position.

The dominant feature of our design resides in the portion shown in full lines

W claim:

The new and ornamental design for game board, as shown and described.
